(57) **CLAIM**

I claim the ornamental design for a removable neoprene sleeve for an airport beverage dispenser, as shown and described.

DESCRIPTION

FIG. 1 is a perspective view of one embodiment of a new design for a removable neoprene sleeve for an airport beverage dispenser with the sleeve mounted on the airport beverage dispenser;

FIG. 2 is a front view thereof;

FIG. 3 is a rear view thereof showing a hot weld seam thereof;

FIG. 4 is a left side view thereof;

FIG. 5 is a right side view thereof; and,

FIG. 6 is a top view thereof, the bottom view being a mirror image.

The broken lines in the drawings are included for the purpose of illustration and form no part of the claimed design.
